UNITED STATES PATENT OFFICE

2,480,136

TWO-SPEED DRIVE

John H. Holstein, Chicago, Ill.

Application September 11, 1946, Serial No. 696,328

2 Claims. (Cl. 74—768)

(Granted under the act of March 3, 1883, as amended April 30, 1928; 370 O. G. 757)

1

The invention described in the specification and claims may be manufactured and used by or for the Government for governmental purpose without the payment to me of any royalty thereon.

This invention relates to an improvement in two-speed drives and is designed more particularly to provide a device for traversing the rotatable platform of an anti-aircraft gun mount. In laying an anti-aircraft gun on an aircraft target, it has been found that, if the traversing mechanism has a low gear ratio for the hand wheel drive, the tracker can lay the gun quickly "on" the target. However, such ratio is too coarse to permit accurate tracking of the target, which requires that the traversing device be provided with a high gear ratio sufficiently fine for accurate tracking. Heretofore, traversing devices have had dual driving means to afford the requisite two gear ratios for coarse and fine traversing, which were selective by means of a conventional gear shift. Such devices have proven unsatisfactory for the reason that the necessary operation of the gear shift diverts the attention of the tracker, tending to cause him to lose the target. Also, it is obvious that the functioning of a conventional gear shift necessarily causes a momentary interruption of the gear drive sufficient to seriously affect the operation of the device to prevent the required accuracy of tracking.

This invention provides means whereby the platform can be constantly rotated for coarse and fine traversing of the gun, alternatively, the tracker optionally actuating the device by selection of either of two gear ratios, freely changing from one to the other without interruption of the tracking. Moreover, the structural details of the improved device are so designed and related that the tracker can modify the driving gears without diverting attention from tracking the target.

The particularly novel feature of the improved device is the combination of two sun wheels actuated by the handwheel and provided with sets of planetary gears, respectively, which drive the traversing gear at high and low speed, respectively, and pedal-operated means for selective adjustment for alternative operation of the planetaries. The combination is such that rotation of the handwheel constantly impels the traversing gear uninterfered by the operation of adjusting the planetaries, so that tracking is uninterrupted.

While there is illustrated in the drawings and hereinafter fully described one specific embodi-

2

ment of the invention, it is to be distinctly understood that the invention is not considered to be limited to said specific embodiment reference for its scope being made to the claims appended hereto.

5

In the drawings:

Fig. 1 is a fragmentary side elevation of an anti-aircraft gun and mount, showing the improved traversing device mounted on the rotatable platform of the mount.

10

Fig. 2 is an enlarged top plan of the traversing device shown in Fig. 1.

15

Fig. 3 is a greatly enlarged vertical section on the line 3—3 of Fig. 1, in the direction of the arrows.

20

Fig. 4 is a vertical section on the line 4—4 of Fig. 3, in the direction of the arrows.

Fig. 5 is a horizontal section on the line 5—5 of Fig. 4, in the direction of the arrows.

25

Fig. 6 is a vertical section on the line 6—6 of Fig. 4, in the direction of the arrows.

Fig. 7 is an enlarged vertical section on the line 7—7 of Fig. 2, in the direction of the arrows.

30

Fig. 8 is an enlarged vertical section on the line 8—8 of Fig. 2, in the direction of the arrows.

35

As illustrated in the drawings, the improved device is designed for traversing a 75 mm. anti-aircraft gun on a mobile mount. The gun 1 is carried in the trunnion bearings 2 on the rotatable platform 3 supported on ball bearings (not shown) by the carriage 4. A ring gear 5 on the carriage 4 co-acts with traversing pinion 6, for rotating platform 3 (Fig. 3). Pinion 6 is driven by a vertical shaft 7 journaled in a hollow pillar

40

8 mounted on platform 3, and provided at its upper end with miter gear 9 which is disposed in casing 10 mounted on top of pillar 8. Journaled in casing 10, there is a horizontal driving shaft 11 provided on its end exterior to casing 10 with an operating hand crank 12. Keyed on shaft 11, there is a sun gear 13 meshing with a pair of planetary gears 14 disposed symmetrically on diametrically opposite sides of gear 13 (Figs. 4 and 5) and rotatably mounted on stub

45

shafts 15 mounted in radial arms 16 of a spider 17 rotatably mounted on shaft 11 and provided with a sleeve 18 loose about shaft 11. A miter gear 19 (Fig. 3) is keyed to sleeve 18 and meshes with the miter gear 9 on shaft 7. Keyed on shaft 11, adjacent sun gear 13 (Figs. 3 and 5) there is a second sun gear 20 meshing with a pair of planetary gears 21 disposed symmetrically on diametrically opposite sides of gear 20 (Figs. 3 and 4) and rotatably mounted on stub shafts 22 mounted in radial arms 23 of the spider 17. It

50

55

will be noted (Fig. 4) that the planetary gears 14 and 21 are so mounted on spider 17 that the pair of gears 14 are so disposed relative to the pair of gears 21, that the four planetary gears are symmetrically disposed about driving shaft 11. Planetary gears 14 (Fig. 5) mesh with an internal ring gear 24 on a drum 25 rotatably mounted on sleeve 18, and planetary gears 21 (Figs. 3 and 4) mesh with an internal ring gear 26 on a drum 27 rotatably mounted on shaft 11. It will be noted (Figs. 3 and 5) that the radial arms 16 and 23 of the spider 17 are so relatively dimensioned as to dispose their planetary gears 14 and 21, respectively, in the adjacently disposed drums 25 and 27, respectively, as well as in mesh with the adjacently disposed sun gears 13 and 20, respectively.

Disposed about the periphery of the drum 25, there is a brake-band 28 with a brake lining 29. One end 28-a of the band 28 is adjustably anchored by a pin 30 in a clevis 31 which is swiveled on a bolt 32 threaded in a lug 33 disposed on the interior of an extension casing 10-a of the casing 10. Bolt 32 has a slot 34 in its outer end to allow adjustment of bolt 32 in lug 33, and a lock nut 35 is provided on outer portion of bolt 32. The other end 28-b of the band 28 is attached to pin 36 on crank arms 37 fixed to rock shaft 38 journaled in casing 10-a.

Disposed about the periphery of the drum 27, there is a brake-band 39 with a brake lining 40. One end 39-a of the band 39 is adjustably anchored by a pin 41 in a clevis 42 in which is rotatably mounted a bolt 43 threaded in a lug 44 disposed on the interior of the casing 10-a. Bolt 43 has a slot 45 in its outer end to allow adjustment of bolt 43 in lug 44 and a lock nut 46 is provided on the outer part of bolt 43. The other end 39-b of the band 39 is attached to pin 47 on crank arms 48 splined on rock shaft 38 adjacent arms 37 (Fig. 5).

One end 38-a of rock shaft 38 extends exterior to casing 10-a and has fixed thereon a crank arm 49 pivoted to the female member 50 of a telescopic link, the male member 51 having a crank arm 52 keyed to rock shaft 53. An expansion spring 54 is interposed between members 50 and 51 to bias them apart. Rock shaft 53 is journaled in bearings 55 and 56 mounted on the superstructure of platform 3, and provided on its end adjacent bearing 56 with a crank arm 57 to which is pivoted a pitman 58 (see Figure 7) adjustably pivoted to crank arm 59 on rock shaft 60 journaled in brackets 61 on platform 3. A sleeve 62 fixed to shaft 60 carries a foot pedal 63 having the portion 64 forward of and above the axis of shaft 60, and the portion 65 to the rear and below the axis of shaft 60.

A seat 66, for the operator of the device, is so disposed on platform 3 relative to handle 12 and pedal 63 that the right hand and right foot of the operator are positioned for operation of handle 12 and pedal 63, respectively.

From the foregoing description of the details of construction of the device, its use and operation are obvious. When the parts are positioned as shown in the drawings, the pedal 63 through its linkage to shaft 53 holds the telescopic link 50-51 expanded to position link 49 downwardly (Figs. 2, 5 and 8), thereby positioning rock shaft 38 to cause crank arms 48 to tension brake-band 38 about drum 27 sufficiently to prevent its rotation (Fig. 4). It will be noted that the crank arms 37 and the crank arms 48 are so relatively disposed on rock shaft 38 that when arms 48 tension

5 band 39 on drum 27, the arms 37 are positioned to relax brake-band 28 from drum 25 to permit its rotation, and vice-versa. The drum 27 being braked, it is obvious (Fig. 4) that, when sun gear 26 is rotated by shaft 11 driven by crank 12, it will cause its planetaries 21 to travel on ring gear 26 on stationary drum 27, thereby rotating spider 17, on which planetaries 21 are mounted, and through sleeve 18, miter gears 19 and 9, shaft 7 with its pinion 6, and ring gear 5, rotate platform 3 about its axis, relative to carriage 4, traversing gun 1. Because of the relative diameters of the sun gear 26 and its planetaries 21 (Fig. 4), the gun 1 is traversed at the higher speed suitable for laying the gun quickly "on" the target. As above described, the device is normally conditioned for this form of traversing. Should the operator wish to shift from high speed, coarse traversing, after he has laid the gun "on" the target, to low speed, fine traversing for accurate tracking, he rocks pedal 63 to depress its forward portion 64 (Fig. 7), rocking shaft 60 to move crank arm 59 upwardly, elevating pitman 58 and crank arm 57, to rock shaft 53 (Fig. 1). This movement of shaft 63 swings crank arm 52 upwardly compressing telescopic link 50-51 until it passes dead-center (Fig. 8) when it expands, under force of spring 54, to its position shown in dotted lines. This action raises crank arm 49, rocking shaft 38 to cause arms 37 to tension brake-band 28 about drum 25 to prevent its rotation and simultaneously cause arms 48 to relax band 39 from drum 27 to permit its rotation.

It will be noted (Fig. 3) that during the above-described operation of high speed traversing, sun gear 13 is rotated by shaft 11, driving its planetaries 14, and that while planetaries 14 travel with spider 17 on which they are mounted, they exert no driving impulse to spider 17 since they merely rotate loose drum 25 through its ring gear 24. However, when drum 25 is braked, as above described, planetaries 14 then exert driving force on spider 17 which has been relieved of the driving force of planetaries 21 since their drum 27 has been released to rotate. Because of the relative diameters of the sun gear 13 and its planetaries 14 (Fig. 5), the gun 1 is now traversed at the lower speed suitable for accurate tracking.

It is obvious that should operator wish to restore the parts to normal position for high speed traversing, he rocks pedal 63 to depress its rear portion 65, the action reversing the movements above described.

It will be noted that the biased telescopic link 50-51 serves to produce a snap action on the crank arms 37 and 48.

Having described my invention, what I claim is:

1. In a multi-speed drive for angularly moving a gun, the combination of a driving shaft; a spider journaled on said shaft coaxially therewith; four radial arms on said spider; a stub shaft on each arm parallel with said driving shaft; a planetary gear journaled on each stub shaft, said four gears being symmetrically disposed about said driving shaft and comprising two sets of two gears each, the two gears of each set being on diametrically opposite sides of said driving shaft, said two sets being relatively spaced axially of said driving shaft; a pair of sun gears of different pitch diameters fixed on said driving shaft each meshing with the planetary gears of a respective set; said spider including a sleeve journaled on said driving shaft; a driven shaft; gear means connecting said sleeve and said driven

shaft; a first drum journaled on said driving shaft; a second drum journaled on said sleeve, each of said drums having an internal ring gear, each said ring gear meshing with the planetary gears of a respective one of said sets; first and second brake bands each contractible about a respective drum to brake the same, a first shaft movable from a first to a second rotative position, means operated by said shaft when in said first position to contract said first brake band and simultaneously release said second band and when in second position to contract said second brake band and simultaneously release said first band, and manually operated snap action means for moving and yieldingly holding said first shaft in a selected one of said two positions.

2. In a drive as recited in claim 1, said last-named means comprising a second shaft parallel with said first shaft, first and second levers fixed to each shaft, one said lever comprising first and second telescoping parts, spring means urging one part radially outwardly, and means pivotally connecting said one part and the distal end of the other of said levers.

JOHN H. HOLSTEIN. 25
